UNITED STATES PATENT OFFICE.

ABRAM ALLEN STILL, OF ANNENETTE, CALIFORNIA.

GATE-LATCH.

1,200,260.

Specification of Letters Patent.

Patented Oct. 3, 1916.

Application filed April 15, 1916. Serial No. 91,503.

To all whom it may concern:

Be it known that I, ABRAM A. STILL, a citizen of the United States, and a resident of Annette, in the county of Kern and State 5 of California, have made an Improvement in Gate-Latches, of which the following is a specification.

My invention is an improvement in the class of latches which are pivoted to a gate 10 post in horizontal position and adapted to engage the free edge of a gate when swinging from either direction.

The details of construction, arrangement and operation of the parts forming my im- 15 proved latch are as hereinafter described with reference to the accompanying drawing, in which:

Figure 1 is a longitudinal section of the latch engaged with a lug applied to a swing- 20 ing gate. Fig. 2 is a face view of the latch tilted or inclined as when being opened. Fig. 3 is a vertical section on line 3-3 of Fig. 1. Fig. 4 is in part a plan view and in part a longitudinal section of the latch. 25 Fig. 5 is a reduced cross section on line 5-5 of Fig. 1.

The latch proper K is a bar which tapers from the middle toward the ends A, which serve as handles in opening the latch. The 30 underside of the handles is practically straight and inclined slightly upward from the central notch J to facilitate engagement of the latch with the lug H which projects laterally from the free edge of the gate, as 35 shown in Fig. 1.

The latch is fixed on the head of a rocking bolt B, that extends through and is held in a housing formed of a vertical plate E and a tube D which is a rigid and permanent at- 40 tachment of said plate. A nut C is applied to the rear end of the bolt B exterior to the tube, and serves to prevent withdrawal of the bolt without interfering with its rocking function.

45 The diameter of the bolt B is much less than that of the tube D, and a plate spring I is secured to the bolt at a point adjacent to the outer end and its free end is curved upward into frictional engagement with the tube D, as shown in Fig. 1. Thus the spring holds the bolt pressed normally downward into contact with the under side of the tube D as shown in Figs. 1 and 3.

50 The housing plate E has two vertical slots F arranged on opposite sides of the tube D, see Figs. 2 and 3, and these slots receive

lugs or studs G projecting from the inner side of the plate E, as shown in Fig. 4. The housing E and tube D have an attachment E', shown in Fig. 4, which serves as means 60 for securing the device to a post.

It will be seen that when the gate is closed, as in Figs. 1 and 3, the gate lug H lies in the notch J of the latch K; and that to open the gate the operator seizes and 65 raises one of the handles A of the latch, as shown in Fig. 2, so that it is released from the gate lug H and permits the gate to swing open. In this tilting operation of the latch, the bolt B is rocked or rotated to 70 a corresponding degree, and at the same time raised against the pressure of the spring I.

When the latch K is closed, the lugs G 75 rest at the bottom of the slots F in the hous- ing plate E, as shown in Fig. 3. Thus the latch is held level or horizontal and in due position to operate as required. When the latch is tilted, the lugs G are guided by the slots in the vertical movement of the latch 80 and bolt.

I claim:

1. The improved gate-latch comprising the latch proper, having its ends extended laterally and provided with a central notch 85 in its underside, a bolt whose free end carries said latch and is adapted for swinging movement, and a housing for the bolt whose diameter allows such movement, as de- 90 scribed.

2. The improved gate latch comprising a latch proper having its ends extended laterally and provided with a central notch on its underside, a bolt whose free end carries said latch and is adapted to rock and 95 swing, as described; a housing for said bolt which allows such movement, a spring ar- ranged in the housing and serving to de- press the bolt, and hold the latch proper nor- mally in position for engaging the gate, sub- 100 stantly as described.

3. The improved gate latch comprising a latch proper having its ends extended lat- 105 erally and provided with a central notch and lugs on its rear side, a horizontal bolt on which said latch is supported, the front end of said bolt being free to rotate, and swing vertically and horizontally, a housing for the bolt including a plate having verti- cal slots and a spring arranged in the hous- 110 ing and acting on the bolt to hold it in nor- mal position, as described.

4. The improved gate latch comprising a notched latch having lugs on its rear side and its ends extended, the underside of the end portions being inclined upward and 5 horizontally, a rocking bolt on which the latch is fixed, a tube in which the said bolt is inclosed with freedom of vertical and lateral movement, a spring arranged in said tube and pressing upon the bolt, and a plate

fixed on the head of said tube and having 10 vertical slots to receive the lugs of the latch and guide the latter in its vertical movement, as described.

ABRAM ALLEN STILL.
